UNITED STATES PATENT OFFICE.

WILLIS II. DENSON, OF CORNING, NEW YORK.

DESIGN FOR A PUZZLE-BOX.

SPECIFICATION forming part of Design No. 30,073, dated January 24, 1899.

Application filed December 31, 1898. Serial No. 700,855. Term of patent 7 years.

To all whom it may concern:

Be it known that I, WILLIS II. DENSON, a citizen of the United States, residing at Corning, in the county of Steuben and State of New York, have invented and produced a new and original Design for a Puzzle-Box, of which the following is a specification.

This invention relates to a new and original design for a puzzle-box; and it has for its object to provide a design of this character which shall be both useful and ornamental.

The leading feature of the design resides in a box-body having a flat bottom provided with a marginal upstanding flange and with a centrally-arranged shed elevated therefrom, said shed being of a polygonal configuration and having at opposite diagonal corners vertical pendent legs and between said legs provided with rectangular openings.

The minor features of the design are the box-body having the flat bottom and marginal flange of a rectangular shape and the central elevated shed having an octagonal flat top portion and pendent vertical legs of a rectangular shape.

In the drawings, Figure 1 is a perspective view of a puzzle-box embodying the herein-described design. Fig. 2 is a plan view, partly in section. Fig. 3 is a cross-sectional view on the line 3 3 of Fig. 2.

Referring to the accompanying drawings, the numeral 1 designates a rectangular box-body having a flat bottom board 2, provided

with a marginal or peripheral upstanding flange 3, which conforms to the rectangular configuration of the bottom. The said flat bottom or bottom board 2 of the puzzle-box, in addition to the marginal or peripheral flange 3, is provided upon its upper side and at a central point with an elevated shed 4. The shed 4, which is elevated from the upper field or surface of the flat bottom 2, is provided with a flat top portion 5 of an octagonal shape and having at diagonally opposite corners vertically-disposed pendent rectangular legs 6, attached to the said bottom or bottom board 2. By reason of the pendent legs 6 being arranged at diagonally opposite corners of the elevated shed 4 the adjacent legs are disposed at substantially right angles to each other, as shown in Fig. 2 of the drawings, and between the adjacent pendent legs 6 the elevated shed 4 has the sides thereof pierced by rectangular openings 7, which complete the design for the shed.

What is claimed is—

The design for a puzzle-box, herein shown and described.

In testimony that I claim the foregoing as my own I have hereto affixed my signature in the presence of two witnesses.

WILLIS II. DENSON.
